(57) **CLAIM**

The ornamental design for a display support, as shown and described.

DESCRIPTION

FIG. 1 is a perspective view of a display support showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view in use;

FIG. 9 is another perspective view in use;

FIG. 10 is another perspective view in use; and,

FIG. 11 is another perspective view in use.

The broken lines showing screens in FIGS. 8-11 illustrate the environment of the claimed design and form no part thereof. The remaining broken lines in FIGS. 1, 4, 7, 8 and 10 illustrate portions of the display support which form no part of the claimed design.

1 Claim, 11 Drawing Sheets
